[57] ABSTRACT

This invention relates to the control of herbaceous weeds such as bindweed, maidencane, arrowhead and sedges by applying to the locus of the weeds a compound selected from compounds having the following formula

where

R is alkyl of 1 to 3 carbon atoms, allyl or benzyl;
R₁ is M, alkyl of 1 to 3 carbon atoms, alkenyl of 3 to 4
carbon atoms or benzyl;
M is lithium, sodium, potassium or ammonium;
X is oxygen or sulfur; and
Y is oxygen or sulfur

with the proviso that when Y is sulfur, X is sulfur.
